United States Patent [19]

Heimburger

[11] Patent Number: Des. 319,632

[45] Date of Patent: ** Sep. 3, 1991

[54] MULTI-FUNCTIONAL KEYBOARD FOR DATA PROCESSING SYSTEMS

[75] Inventor: **Alfons Heimburger**, Niedereschach, Fed. Rep. of Germany

[73] Assignee: **Mannesmann Kienzle GmbH**, Villingen, Fed. Rep. of Germany

[**] Term: **14 Years**

[21] Appl. No.: **347,412**

[22] Filed: **May 3, 1989**

[30] Foreign Application Priority Data

Nov. 8, 1988 [WO] World Int. Prop. O. DM/012143

[57] CLAIM

The ornamental design for a multi-functional keyboard for data processing systems, as shown and described.

DESCRIPTION

FIG. 1 is a top plan view of a multi-functional keyboard for data processing systems showing my new design;

FIG. 2 is a left side elevational view thereof;

FIG. 3 is a rear elevational view thereof;

FIG. 4 is a bottom plan view thereof;

FIG. 5 is a right side elevational view thereof;

FIG. 6 is a sectional view thereof;

FIG. 7 is a left side elevational view thereof with an interpretation template attached and in raised position;

FIG. 8 is a left side elevational view thereof with a reader attached;

FIG. 9 is a left side elevational view thereof with the template raised and the reader attached;

FIG. 10 is a bottom plan view thereof with the reader attached;

FIG. 11 is a rear elevational view thereof with the template raised and the reader attached;

FIG. 12 is a top, front, right side perspective view thereof with the template cut away and in raised position and with the reader attached.
